COMBINED BROCHURE DISPENSER AND DISPLAY CABINET

Charles B. Crawford, Chevy Chase, and Frederick G. Goodwin, Rockville, Md., assignors to Markets Advertising Corporation, a corporation of the District of Columbia

Filed Oct. 25, 1962, Ser. No. 72,255

Term of patent 3½ years

(Cl. D80—11)

FIG. 3.

FIG. 4.

FIG. 5.

FIG. 6.

FIG. 1 is a front elevational view of a combined brochure dispenser and display cabinet showing our new design;

FIG. 2 is an elevational view taken from one side thereof, the opposite side being a mirror image of the side shown;

FIG. 3 is a top plan view thereof;

FIG. 4 is a sectional view taken on the line 4-4 of FIG. 1;

FIG. 5 is a sectional view taken on the line 5-5 of FIG. 1; and

FIG. 6 is a sectional view taken on the line 6-6 of FIG. 1.

The dominant features of our design reside in the full line portions of the drawing.

We claim:

The ornamental design for a combined brochure dispenser and display cabinet, as shown and described.
